UNITED STATES PATENT OFFICE.

NORMAN O. FLEMING, OF HUNTINGTON PARK, CALIFORNIA.

AIR-CHAMBER FOR PUMPS.

1,290,155.

Specification of Letters Patent.

Patented Jan. 7, 1913.

Application filed April 23, 1912. Serial No. 184,073.

To all whom it may concern:

Be it known that I, NORMAN O. FLEMING, a citizen of the United States, residing at Huntington Park, in the county of Los Angeles and State of California, have invented a new and useful Air-Chamber for Pumps, of which the following is a specification.

My invention relates to pumps, and the principal object of the invention is to provide means for equalizing the pressure delivered by a plunger pump.

In the operation of plunger pumps, particularly those having a single piston, the rate of flow varies from zero to a maximum during each cycle of the pump, and this variation in the rate of flow prevents the pump from having a large capacity, as the column of water must be accelerated and stopped during each stroke, and the frictional losses at the maximum speed are likely to become excessive. In my invention I provide means for producing a relatively uniform discharge from the top of the pump column even where single acting pumps are used, this equalization of the pressure being accomplished by the use of an air cylinder located inside the pump column.

A further object of my invention is to provide means by which the operator of a pump can tell at any time the depth of water in the well.

Referring to the drawings, which are for illustrative purposes only:

Figure 1 is an elevation, partly in section, of a portion of a well with my invention installed therein, the parts being shown in their operative or working positions.

Fig. 2 is a similar section showing the method of removing the various parts from the well.

Fig. 3 is a section on a plane represented by the line 3-3 Fig. 1, and

Fig. 4 is a section through a conventional form of a three-way valve.

In the embodiment of my invention shown in the drawings, a casing 11 is shown inside the well to which the invention is to be applied. Secured on suitable foundations, by means of bolts 12, is a sole plate 13 on which a discharge T 14 rests, this discharge T being fastened down by means of bolts 15. Secured in the lower end of the discharge T by means of a thread 16 is a pump column 17, and secured to the bottom of the pump column 17, by means of a collar 18, is a pump barrel 19 in which a piston 20 of

any convenient form may operate. The piston 20 is actuated by a string of pump rods 21, these pump rods extending up through a cover 22 secured by bolts 23 on top of the discharge T 14, a stuffing box 24 being provided around the pump rods 21 where they pass through the cover 22. A seat 25 is formed inside the discharge T 14, and an air retainer ring 26 is properly shaped to be seated thereon. Threaded in the air retainer ring 26 is an air retainer 27, this air retainer 27 being a cylindrical pipe and being of sufficient length to extend down into the interior of the pump column 17 for a considerable distance.

For the purpose of holding the air retainer ring 26 on the seat 25, I provide a clamping pipe 30, this clamping pipe being secured to a clamping ring 31 at its upper end. The clamping ring 31 is forced downwardly inside the T 14 by means of bolts 32, the lower end of the clamping pipe 30 resting on top of the air retainer ring 26. An opening 33 is provided in the top of the clamping pipe 30 through which water may discharge.

For the purpose of supplying air to the space 40, between the pump column 17 and the air retainer 27, I provide a compressed air reservoir 41 which is constantly supplied with compressed air from any suitable source, not shown. For example, this source may be a small pump actuated by the mechanism of the pumping head, or it may be any independent source of supply. A supply pipe 42 is provided, connecting with the interior of the air chamber 41 and connecting with the interior of a gage 43, this gage being calibrated in feet of submergence of water, in the place of pressure. A three-way valve 44 is provided, said valve being so arranged as to connect the pipe 42 to either a pipe 45 or a pipe 46, a conventional type of such valve being shown in section 160 in Fig. 4. Pipe 45 connects to the space 40, and the pipe 46 extends downwardly to a considerable distance below the surface of the water 47 in the well.

The method of operation is as follows:

The valve 44 being suitably manipulated, air from the reservoir 41 flows into the space 40, forcing the water level therein downwardly to any desired degree, the valve 44 being manipulated to connect the pipe 42 with the pipe 46. Compressed air flows downwardly through the pipe 46 and up-

wardly through the surface of the water in the well, the pressure in this pipe being determined by the distance from the surface of the water 47 to the bottom of the pipe 46. 5 or, in other words, by the submergence of the pipe, the gage 43 being calibrated in inches of water rather than in terms of pounds per square inch. This submergence can be instantly read in feet, and the length of the 10 pipe 46 being known, the depth of water in the well can be readily ascertained. The piston 20 being actuated through the pump rods 21, a variable water flow is produced upwardly through the pump column 17, and 15 a variable pressure is produced at the bottom of the air retainer 27. As this pressure increases on the upward stroke of the piston 20, the air in the space 40 is compressed and the flow through the space between the air 20 retainer 27 and the pump rods 21 is reduced, this flow being considerably less than the maximum flow which would occur with no air in the space 40. Whenever the piston 20 stops its motion, or starts to move down- 25 wardly, the air in the space 40 expands, forcing the water level downwardly and maintaining the flow upwardly through the interior of the air retainer 27. It will therefore be seen that the air in the space 40 is 30 compressed on the up-stroke and expands on the down-stroke, thereby maintaining a relatively uniform flow of water from the pump. When it is desired to remove the piston 20 from the well, the cover 22 is taken 35 off and the bolts 23 are removed, thereby releasing the clamping ring 31. The pump rods 21 being then raised, the air retainer 27 rests on the top of the piston 20, as shown 40 in Fig. 2, and the parts 27, 26, 30 and 31 are removed from the well together.

I claim as my invention:

1. In a pump, a pump column; a pump rod passing through said pump column; an air retainer in the upper portion of said 45 pump column and around said pump rod; an air retainer ring secured to the upper end of said air retainer; a discharge T secured to the upper end of the pump column; a cover secured on the top of said discharge 50 T; and means independent of said cover for

forcing said air retainer ring into air tight relationship with a seat formed in said discharge T.

2. In a pump, a pump column; a pump rod passing through said pump column; an air retainer in the upper portion of said pump column and around said pump rod; means for supplying compressed air to the space between said air retainer and the upper end of the pump column; an air retainer 60 ring secured to the upper end of said air retainer; a discharge T secured to the upper end of the pump column; a cover secured on the top of said discharge T; and means independent of said cover for forcing said air 65 retainer ring into air tight relationship with a seat formed in said discharge T.

3. In a pump, a pump column; a pump barrel secured to the lower end of said pump column; a piston sliding freely in said pump 70 barrel; a string of pump rods passing through said pump column and secured to said piston; an air retainer surrounding said rods and projecting downwardly into said pump column, said air retainer having an 75 inside diameter considerably less than the outside diameter of said piston; and means for detachably securing the upper end of said air retainer in air tight relationship with the said pump column.

4. A combination as in claim 3 in which said means comprises a discharge T into which the upper end of said pump column is secured in air tight relationship; a seat formed on said T; an air retainer ring secured to the upper end of said air retainer; and clamping means for forcing said air retainer ring into air tight relationship with said seat.

5. A combination as in claim 4 in which 90 said clamping means comprises a clamping pipe resting on said air retainer ring inside said discharge T; a clamping ring resting on said clamping pipe; and bolts threaded in said discharge T and passing through 95 said clamping ring.

In testimony whereof I have hereunto set my hand at Los Angeles, California, this 16th day of April, 1917.

NORMAN O. FLEMING.
